are at you.

UNITED STATES PATENT OFFICE

WILLIAM S. ELLIOTT, OF PITTSBURGH, PENNSYLVANIA

CONDENSER

Application filed April 15, 1925, Serial No. 23,278.

The present invention relates broadly to heat interchange and liquid treatment, and more particularly as applied to condensers of the type adaptable for use in power plants and the like.

In power plant work, it is desirable to deliver condensate from condensers at temperatures as high as possible, in order to thereby conserve heat and reduce the amount of heat subsequently required for bringing the condensate to a temperature at which it may be efficiently re-used.

It is well recognized at the present time that the air dissolved in water is responsible, to a large extent, for the corrosion which takes place in power plant equipment, and many efforts have been made to effect its elimination. The solubility of air in water is a function of the temperature, the solubility decreasing as the temperature increases. From the standpoint, therefore, of deaeration, it is also of material advantage to keep the temperature of the condensate as high as possible, to thereby proportionately decrease the air content.

It has heretofore been proposed in the art to which the present invention relates to provide condensers of such construction that it is possible to raise the temperature at which the condensate leaves the condenser. While, as before stated, the higher temperatures insure a lower air content, I have found that in order to produce water having a zero oxygen or air content, or extremely low amounts of air it is desirable to subject the condensate not only to higher temperature conditions of the character referred to, but also agitation under such conditions as to facilitate air separation.

In operating condensers under such conditions as to produce a high condensate temperature, the capacity range of the condenser must be considered and conserved. For example, if free steam is utilized for raising the condensate temperature, provision must be made for controlling the volume of steam in such manner that an excess will not be supplied to any zone of the condenser in such manner as to effect an overloading thereof with a consequent diminution in the ability

of the condenser to perform that work for which it was designed.

The present invention, therefore, has for certain of its objects the provision of a condenser operating to produce not only a high temperature condensate, but a condensate substantially free from dissolved or entrained air, and at the same time operating under such conditions that the capacity of the condenser is not impaired.

In the accompanying drawings there is shown for purposes of illustration only, a preferred embodiment of the present invention, it being understood that the drawings do not define the limits of my invention as changes in the construction and operation disclosed therein may be made without departing either from the spirit of the invention or the scope of my broader claims.

In the drawings:

Figure 1 is a vertical sectional view on the line I—I of Figure 2;

Figure 2 is a longitudinal sectional view along the line II—II of Figure 1, certain of the parts in both figures being shown in elevation;

Figure 3 is a detail sectional view on an enlarged scale, illustrating a portion of the bottom of the condenser, and

Figure 4 is a view illustrating in perspective a skeleton of the interior construction of the condenser.

In the illustrated embodiment of the invention, I have shown a condenser of the general construction disclosed in the patent to Raymond N. Ehrhart, No. 1,522,290 granted January 6, 1925. It will be understood, however, that the advantages of the invention are not limited to a condenser of this type, but that it is adapted to a wide variety of different condensers.

In carrying out the present invention there may be provided a condenser of any desired construction, herein shown as having a casing 2 carrying a plurality of longitudinally extending tube banks or tube nests 3. The condenser may be provided with one or more headers 4, as well understood in the art, for controlling the delivery or discharge of cooling water to the tubes. With a condenser of

the character shown, cooling water may be delivered to the inlet connection 5 of the header 4 which will deliver the water to the lower tubes through which it will pass in parallel to a header (not shown) on the opposite end of the condenser effective for returning the water through the upper tubes from which it will be discharged into the header 4 and withdrawn through an outlet 6.

10 Cooperating with the condenser in any desired manner, and located at any convenient point, is a steam passage 7 communicating at its upper end with the steam inlet or vapor space 8 of the condenser. The passage 7 in the illustrated embodiment of the invention is shown as formed by spaced plates 9 extending longitudinally through the central portion of the condenser and terminating short of the bottom of the casing 2 above a condensate heating chamber 10 into which the passage 7 discharges.

15 Cooperating with the passage at any desired point is an air offtake 11 which may vent directly to the atmosphere or may cooperate with an air withdrawing means such as a pump or ejector (not shown). The offtake has inlet openings 12 through the plates 9, the air being directed into these offtakes from a lower portion of the condenser by 20 means of deflectors or baffles 13.

25 The condensing zone of the condenser may be divided from the condensate chamber 10 by a diaphragm 14 having a plurality of openings 15 for the passage of condensate from the condensing chamber into the condensate chamber. These openings are preferably positioned so as to provide a plurality of jets, effective for breaking up the condensate into a plurality of streams and thereby 30 facilitating the heating thereof. The diaphragm is further provided with one or more openings 16 surrounded by flanges 17 preventing the flow of condensate therethrough while permitting the free passage of vapors 35 and gases. In this manner there are provided separate flow paths for the condensate entering the condensate chamber and for the vapor or gases flowing in the opposite direction into the condenser for withdrawal 40 through the offtake 11.

45 Mounted within the condensate chamber in different horizontal planes are combined heating and agitating means dividing the condensate chamber into super-imposed compartments. These heating and agitating means are herein illustrated as comprising a lower tray section 18 and an upper tray section 19. The upper tray section directly receives condensate through the openings 15, the condensate flowing over this tray section to openings 20 which discharge onto the lower tray section. The condensate in turn flows in broken up film-like condition over the 50 lower tray section to an outlet 21 discharging

into the bottom of the condenser casing and in turn into the hot well 22.

55 The path of steam to the heating and agitating trays is determined by providing the condenser with a partition 24 between the plates 9 and forming a bottom for the main portion of the length of the passage 7. This partition has a substantially centrally located opening 25 through which the steam passes to the space T between the sections of the tray 19, as indicated by the arrows 26.

60 An intermediate support 27 for the condenser tubes may be provided, as well understood in the art.

65 In actual operation of a condenser, the steam entering the condenser is always at a higher temperature than the temperature prevailing at the bottom of the condenser due to the drop in pressure through the condenser. If sufficient heat can be added to the condensate leaving the condensing chamber, so as to maintain in this condensate a temperature equal, or substantially equal, to the temperature of the condenser, and the condensate can be broken up and agitated at this 70 temperature, air or other gas will be effectively released therefrom. Unless effective means is provided, however, for removing the released gases, a partial air pressure will be built up which will interfere with successful 75 deaeration. At the same time, if an unrestricted quantity of steam is utilized for heating the condensate so that there is a through flow of steam in the condensate chamber, this steam will pass into the lower portion of the 80 condenser and flood the tube area with free steam, thereby cutting down the capacity of the condenser and interfering with its 85 efficient operation.

90 With the construction herein illustrated, the condensate leaves the condenser in the form of a plurality of jets in such condition that efficient heat interchange may take place. This condensate then flows in broken-up condition over a tray surface and thence in similar condition over another tray surface. 95 Steam flows downwardly through the passage 7 into the compartment T between the trays. The steam flows horizontally through this compartment as indicated by the arrows (i), 100 thereby tending to sweep any released air from such compartment to the spaces 23 provided at the ends of the trays. This steam in turn passes upwardly and travels horizontally in the upper compartment I in the 105 direction indicated by the arrows (i). The passage 7 is of such size relative to the passageway for steam through the tube nests as to provide the amount of steam which the condensate from the tube nests is capable of condensing. Under these conditions, if the 110 amount of condensate passed to the condensate chamber increases, there will be a correspondingly greater steam condensing capacity. There will also be a corre- 115

spondingly greater steam flow through the passage 7 and the heater T in order to meet the increased demands of the condensate. On the other hand, if the amount of condensate decreases, the steam condensing capacity will be less, and a correspondingly smaller amount of steam will be condensed. At no time will there be such an excess of steam for passage through the gas and vapor outlet 16 as to impair the condensing capacity of any portion of the condenser. What little steam passes through the opening or openings 16 will be condensed by the tubes below the deflectors 13 and located adjacent the flow terminus through the condenser. These tubes will be effective for abstracting any further heat both from the vapor and from the gases, thereby preventing the waste of heat through the offtake 11. This automatic control of the heating steam for the condensate is thus particularly advantageous, as it not only prevents flooding of the condenser, but also always insures a sufficient supply of steam to raise the temperature 25 of the condensate to the desired point.

Efficient deaeration requires the maintenance of definite temperature and pressure conditions. The heater automatically operates to maintain these conditions, and thereby insures at all times the release of air and gas from the condensate.

The construction described is further advantageous in that the flow of steam causes any released air to be swept from the compartment T into the compartment thereabove. The construction is such as to produce a counter flow of condensate and steam of such nature that the steam first contacts with the condensate in the compartment T and later contacts with the condensate in the compartment I, all of the steam supplied to the compartment I, however, being delivered from the compartment T. This construction insures a condition in which the major heating duty is continuously performed by the heater I, the condensate being delivered by such heater to the heater T at a temperature substantially equal to the temperature of the heating steam. This operation is advantageous as it relieves the heater T from any substantial heating duty, and consequently enables it to function efficiently as a deaerator due to the possibility of maintaining a low air tension or partial air pressure therein. By the provision of the heater I, this partial air pressure is maintained below that point which would obtain if the heater T were acting singly.

It will be apparent to those skilled in the art, that the advantages of the present invention arise from the provision of a condenser capable of delivering deaerated condensate at a high temperature and operating under such conditions that the capacity of the condenser is not lessened and temperature

conditions are always maintained of such nature as to insure efficient air removal.

I claim:

1. The combination with a condenser, of a chamber receiving condensate from the condenser and having a deaerating tray section and a heating tray section over which the condensate from the condenser flows, and connections for supplying heating steam to said tray sections in series, with the deaerating tray section first receiving steam and causing the steam to flow over both of said tray sections in direct contact with the condensate. 70
2. The combination with a condenser having an inlet, of a chamber receiving condensate from the condenser and having a deaerating tray section and a heating tray section, and means for supplying a portion only of the steam from said inlet to said tray sections in series, with the deaerating tray section first receiving steam. 80
3. The combination with a condenser, of a chamber receiving condensate from the condenser and comprising a deaerating compartment and a heating compartment, means for passing condensate through both of said compartments in series in direct contact with the steam therein, and means for supplying heating steam to said compartment in series, 90 with the deaerating compartment first receiving steam.
4. The combination with a condenser having an inlet, of a chamber receiving condensate from the condenser and comprising a deaerating compartment and a heating compartment, and means for supplying a portion only of the steam from said inlet to said compartments in series, with the deaerating compartment first receiving steam. 100
5. The combination with a condenser, of a chamber receiving condensate therefrom, and heating superimposed trays in said chamber producing a flow of heating steam thereto, said heating means providing separate flow paths for the steam and condensate and being effective for producing a steam flow horizontally through said chamber in contact with the condensate for sweeping released air from said chamber. 105
6. The combination with a condenser, of a chamber receiving condensate therefrom and having a separate condensate inlet and gas offtake, and means including superimposed trays for supplying heating steam to said chamber and producing a steam flow horizontally through the chamber in contact with the condensate for sweeping released gases therefrom and delivering the same to said offtake. 115
7. The combination with a condenser, of a condensate chamber receiving condensate from the condenser and having a gas offtake, of means in said chamber dividing the same into superimposed compartments through 130

which the condensate flows in series, and means for delivering steam to said chamber for contacting with the condensate in both of said compartments.

8. The combination with a condenser, of a heater and a deaerator for the condensate formed therein, said heater and deaerator including means for reheating the condensate to substantially its boiling point, connections for causing the released vapors and gases to be swept horizontally through and then from the deaerator into the heater, and connections for removing gases from the heater.

9. The combination with a condenser, of a condensate chamber receiving condensate therefrom, a steam supply for said chamber, a gas offtake for said chamber, means dividing said chamber into a lower heating compartment and an upper heating compartment, and means for causing the condensate to flow in series through said compartments in direct contact with the steam therein.

10. A condenser having a condensate heating section and a deaerating section, means for passing condensate through said sections in series in the order named, and means for bringing steam into contact with the condensate in both of said sections in the reverse order.

11. A condenser having a heating section and a deaerating section, means for passing condensate through said sections in series in the order named, and means for by-passing a portion only of the steam from the condenser and bringing such steam into contact with the condensate in both of said sections in a reverse order.

12. A condenser including superimposed compartments, tubes above said compartments, connections for passing the condensate from the region of said tubes through said compartments in series, and means for bringing heating steam from the region of said tubes into direct contact with the condensate in both of said compartments.

In testimony whereof I have hereunto set my hand.

WILLIAM S. ELLIOTT
